UNITED STATES PATENT OFFICE.

FRANZ FICKE, OF NEW YORK, N. Y.

TOILET-CASE.

SPECIFICATION forming part of Letters Patent No. 293,568, dated February 12, 1884.

Application filed July 16, 1883. (No model.)

To all whom it may concern:

Be it known that I, FRANZ FICKE, a citizen of the United States, residing at New York, in the county of New York and State of New York, have invented certain new and useful Improvements in Toilet-Cases, of which the following is a specification, reference being had to the accompanying drawings, forming part thereof.

10 Figure 1 is a perspective view of this device with the cover open; Fig. 2, a plan of the inside of the cover; Fig. 3, a plan of the inside of the body of the case; Fig. 4, a detail of a corner, showing the covering crimped and ready to be 15 applied; Fig. 5, a detail in section of the seat for the comb.

This invention relates to toilet-cases; and the novelty consists in the means for holding the hand-mirror in place in the cover, in the 20 means for holding the comb in the body, or tray of the case, and in the finish for the corners of the case, and the device as a whole, all as will now be more fully set out and explained.

25 In the accompanying drawings, A denotes the body or tray of the case, and A' the cover. These are hinged together as usual.

In the cover A', beneath the ornamental lining a, are the side springs, b, overlapping the mirror B when in position in the cover, and 30 thus securely holding it in place. At the sides of the handles are the spring-stays b', which will act as guides, and also prevent any side movement of the handle. These stays b' could be made like the side springs, b, so as 35 to prevent the handle from any downward movement when the case is shut; but this is not at all essential.

In the body or tray A, beneath the ornamental lining a', are the curved springs d, 40 which are intended to come over the handle of the brush E, and thus hold the brush in position. The comb F is placed parallel with the brush in the seat formed of the inclined pieces g and the spring h, so that when the 45 comb is thrust between these parts it will be held sufficiently firm.

Heretofore it has been customary to cover the base of these boxes with stripes of fancy-colored leather or plush, or any desired material, of like length with the side to be covered, its ends cut away to meet at the exact corner, with the piece on the adjoining side cut away in the like manner. In my device I can use one strip, I, for the entire base

A", and instead of cutting away the corner, 55 I bend the corner part in, and then crimp or tuck each side i', so as to make an ornamental half-elliptical finish, i. The strip I, being well covered on its inner side with glue or like material, can be readily fashioned as 60 above, and when the adhesive substance has dried, the corner i will be about as firm as if it had a wire form beneath. The ends of the piece are matched at any desired place between the corners.

In placing the mirror in its seat, it is only necessary to put its back flat upon the springs b, which are so shaped that a slight pressure on the mirror will thus cause them to open and allow the mirror to be put in position, 7c while in removing the mirror it is only necessary to take hold of the handle and raise it upwardly, which action causes the sides of the mirror-back to open the springs, and the mirror is thus readily freed.

75 I am aware that toilet-cases have been made with springs for holding the mirror and the brush in position, and I do not broadly claim such construction as my invention.

What I do claim is—

1. In a toilet-case having a textile cover, I, uncut and folded at the corners i, as described, the combination of the tray A, having the inclined comb-seat g h and spring, with the cover A', having mirror side springs, b, and 85 the guides b', all constructed substantially as described.

2. In a toilet-case, the combination of the tray A, the inclined partition or comb-seat g h, and the spring, substantially as described. 90

3. In a toilet-case, the tray A, having brush-handle springs d, and the comb-seat g h, in combination with the cover A', having the mirror side springs, b, the handle guides or stays b', and the flexible covering, substantially as described. 95

4. A toilet-case having a textile cover, I, uncut at the corners i, which are folded or crimped and lapped at the upper edge and finished, substantially as described.

100 In testimony whereof I have signed my name to this specification in the presence of two subscribing witnesses.

FRANZ FICKE.
